UNITED STATES PATENT OFFICE.

WILLIAM TARRANT, OF PETERSHAM, NEW SOUTH WALES.

CONCENTRATOR.

SPECIFICATION forming part of Letters Patent No. 537,945, dated April 23, 1895.

Application filed October 6, 1894. Serial No. 525,124. (No model.)

To all whom it may concern:

Be it known that I, WILLIAM TARRANT, mining engineer, a subject of the Queen of Great Britain, residing at Weston Street, Petersham, near Sydney, in the British Colony of New South Wales, have invented a new and useful Concentrator, of which the following is a specification.

This invention relates to an improved shaking-table machine for concentrating finely divided or discrete metalliferous material caused to flow through such machine with water and (when the shaking table is formed of amalgamating plates) for amalgamating gold and silver contained in such material.

This invention has been devised in order to produce a cheaply constructed and easily operated machine for such purposes.

This improved shaking-table concentrating machine usable also as an amalgamator is constructed with a circular shelving plane or table or inverted conical dish to which a shaking and percussive motion is imparted to which the material to be treated is continuously fed and from which there is a continuous discharge of the gangue and preferably from which there is a regularly intermittent discharge of concentrates; but in order that this invention may be clearly understood reference will now be made to the drawings here-with, in which—

Figure 1 is a central sectional elevation of a concentrating machine constructed according to this said invention, and Fig. 2 is a plan partly in section of the same.

The circular table or conical dish A is supported on ring or hoop A' having cross stays A^x and which ring is suspended by hooks A² to bars or bracket pieces A³ from the main framing and is pivoted by eye piece A⁴ on pivot bracket A⁵ also on the main framing. Diametrically opposite to the pivot is a pin piece A⁶ on which takes the end of connecting rod B⁸ to a crank pin B² in disk B' on main shaft or spindle B in bearings B⁴ on the main framing. Brackets or L-pieces A⁷ from the framing hold on bolts A⁸ india rubber blocks A⁹ forming buffers to impart the percussive motion to the table or dish when it is reciprocated by the revolution of main shaft B. A conical distributing surface or spreader C is supported by a subsidiary upper framing

above the table or dish A and has above its apex a hopper C' having preferably within it a grating or sieve C². Through the center of the table or dish A a discharge pipe D protrudes upwardly not quite to the level of the top edge of said table or dish so that the discharge of said table or dish takes place from that level. This pipe D passes through an annular discharge passage E for the concentrates and extends downwardly through a receiver for said concentrates to a launder or trough D' to waste. Suspended above the contents level of the table or dish A and hanging below that level is a ring F of blanketing or other woolen or fibrous material which is sewed on to ring or hoop F' through holes therein said ring or hoop being soldered or otherwise fixed on the under side of distributor or spreader C.

A machine constructed as described and explained would work effectually though the concentrates gathered on the table or dish A around pipe D would have to be withdrawn by an attendant at intervals as required through a door or closing piece to passage E; but it is preferable that the discharge of concentrates should be automatic and this is brought about by the mechanism now to be described. The passage E terminates in a valve seating E' against which takes valve piece E² fixed on pipe D. This pipe D carries a basin or director E^x above the receiver or receptacle E^y having inclined bottom E^z. The pipe D and valve E² are intermittently raised and lowered by lever E³ on fulcrum pin E⁵ on bracket E⁶ which lever has back spring E⁷ under compression so that the tendency is for said lever to keep valve E² to its seat E' and passage E closed. The back end of lever E³ is connected by link E⁹ having ball and socket joint E⁸ thereto to bell crank E¹¹ by other ball and socket joint E¹⁰ and this bell crank has U-connection E¹² to rod E¹³ from crank pin in disk E¹⁴ on secondary shaft or spindle E¹⁵ on bearings E¹⁶ and driven through pulleys E¹⁷ and E¹⁸ so that it will revolve considerably slower than main shaft B. The rod E¹³ may be lifted from its U-connection E¹² with bell crank E¹¹ by hand lever E²⁰ on spindle E¹⁹ actuating lever E¹⁸ so that the motion of lever E³ will cease and the intermittent opening of passage E be prevented. The shaft B may be

driven by any suitable means although as preferable cone pulleys B⁶ are shown to be driven from a counter shaft. The main framing consists of sole longitudinal beams G', sole 5 cross beams G², uprights G, top longitudinals G³, top cross beams G⁴ and subsidiary piece G⁵ and the upper framing consists of uprights G⁶, cross pieces G⁷ and bearers G⁸.

In operation the material to be treated is fed 10 with water into hopper C and falling through grating or sieve C' is distributed or spread by passing down the cone surface C dropping upon the outer part of the table or dish A. This table or dish fills with the water and material to the top of pipe D when the discharge 15 of the gangue or waste commences and then any floating gold or surface mineral has to pass the trailing edge of the blanket ring F before discharge is reached and by the nature 20 of the blanketing or woolen or fibrous material such valuable particles are detained and caused to settle upon the table or dish A whence they will pass to the concentrates discharge. The heavier particles or concentrates 25 pass down the inclined plane of the table or dish A and would gather around pipe D but for the automatic discharge which as hereinbefore explained is the regular but intermittent opening of the valve E² on seating E' at 30 bottom of discharge passage E. The gangue or waste passing down pipe D flows through the launder D' to where required while the concentrates falling through passage E³ are directed by basin E^x into receptacle E^y up the 35 inclined bottom E^z of which they may be raked or scraped when desired or necessary.

In use as an amalgamator and concentrator the distributor or spreader C is made of amalgamating or "copper" plates and in use as an amalgamator alone the table or dish A would 40 likewise be made of amalgamating or "copper" plates.

Having now particularly described and explained the nature of my said invention and in what manner the same is to be performed, 45 I declare that what I claim is—

1. In combination with the inverted conical table A, a conical feed plate C covering the table A except at the edge and a ring of fibrous material projecting from the under 50 surface of the feed plate C, substantially as described.

2. In a concentrating machine of the class set forth the combination and arrangement with a table or dish A having a peripheral 55 feed a discharge pipe D and a discharge opening E of a valve seating E' and a valve piece E² on said discharge pipe D and devices by which such valve piece E² is regularly intermittently lifted off and on its seat such as E' 60 substantially as herein described and explained and as illustrated in the drawings.

3. In combination with the table A, the discharge D, the discharge E, the valve closing the latter discharge, means for controlling 65 said discharge, the receptacle E^y and the deflector or basin E^x, substantially as described.

WILLIAM TARRANT.
